UNITED STATES PATENT OFFICE.

JOSEPH H. COPE, OF DENVER, COLORADO.

HAYSTACKER-ANCHORING DEVICE.

Application filed June 15, 1925. Serial No. 37,090.

This invention relates to improvements in the construction of hay stackers of the type described and claimed in United States re-issue Letters Patent No. 15,658, granted to me on July 17, 1923.

In stackers of this type the hay is raised and thrown onto the stack by power derived from horses or from some tractive device such as a tractor or an automobile. The horse or tractor is hitched to one end of a rope whose other end is attached to the stacker arms. When sufficient force is exerted on the rope, the stacker arms will be raised and the hay elevated and deposited on the stack. Since it requires a strong pull to raise the hay, there will be a strong force tending to move the stacker from the position that it should occupy. In order that the stacker shall remain stationary, it must be anchored in some way, as by stakes driven into the ground. This has not proven to be satisfactory as the stakes become loose and as it involves considerable labor. As the stacker is placed up against a stack of hay, it seems that the most logical thing to do would be to anchor the stacker to the haystack and this is what I propose to do.

My invention, briefly described, consists in attaching to the end of the stacker an extension in the form of a brace, which extension is designed to project underneath the stack in such a manner that the hay will keep it from moving. This brace is so constructed that it forms with the stacker a stress triangle which produces a rigid brace structure and which is so designed and assembled that the members of which it is composed can be readily removed from underneath the stack after the latter is completed.

My invention can be most clearly explained and will be most readily understood when reference is had to the accompanying drawing in which it has been illustrated and in which:

Fig. 1 is a side elevation of a stacker showing the brace member attached thereto and in position underneath the stack;

Fig. 2 is a plan view looking downwardly along line 2—2, Fig. 1;

Fig. 3 is an elevation of a portion of the stacker frame and brace showing how the two are connected and showing also how the stacker frame moves the brace members and

Fig. 4 is a detail view showing the manner in which the brace members are connected to each other.

Numerals 1 and 2 represent the base members of a stacker and 3 and 4 the vertical posts to which the stacker arms 5 and 6 are pivoted. To the ends of the stacker arms a stacker head 7 is secured in the usual manner. Uprights 8 and 9 are secured to the rear ends of the stacker frame base members and are connected to the latter by means of braces 10. An A frame 11 is pivoted to the base members at 12 and this has its upper end connected to the stacker arms 5 and 6 by means of links 13. A rope 14 is connected to the A frame near its vertex and passes over the pulleys 15, 16 and 17. The horses are hitched to the free end 18 of the rope. When sufficient force is exerted on the rope, the stacker arms will be raised and the hay will be deposited on the stack. The stacker illustrated and described merely shows the essential parts of a stacker mechanism of the type to which my invention appertains and is intended merely to illustrate my invention and to show the broad combination as my anchoring device may be used in connection with any stacker of this type.

My brace comprises two bars 19 and 20, which are connected to each other and to the base members 1 and 2 in the manner which I will now describe. The bar 19 has a steel plate 21 secured to each side by means of bolts or rivets 22. These steel plates project over the end of the bar and receive between them the end of the base member 1. A pin 23 extends through the plates 21 and the base member 1 in the manner shown. The bar 20 extends diagonally from the end of the base member 2 to the bar 19 and is provided at one end with a bolt 24 that is adapted to enter the hole 25 in the bar 19. To the other end of bar 20 I have secured plates 26 and 27 which extend beyond the end of the bar and receive between them the rear end of base member 2 to which they are connected by means of a pin 28. It will now be evident that the brace bars 19 and 20 together with the transverse frame member 29, form a triangle that is rigid when exposed to a force that makes the bar 19 a tension member.

Referring now to Fig. 2, it will be noticed

that when the stacker is operated, the horses exert a pull on the rope 14 whose direction and intensity may be represented by the arrow F. This force may be resolved into 5 two components represented by arrows P and L which are respectively perpendicular and longitudinal of the frame member 1 and brace member 19. The force P tends to move the stacker to the side and the force L tends 10 to move it longitudinally. Both of these forces are resisted by the braces 19 and 20. The diagonal brace member 20 being held against the ground by the superposed hay cannot move in the direction of arrows L 15 or P, while the bar 19 cannot move in the direction of the arrow L. The stacker is therefore securely anchored. As the stacker arms with the attached stacker head move into vertical position for the purpose of discharging the hay onto the stack, it must be prevented from passing beyond the vertical so far that it will not return and this is guarded against by a rope 30, one end of which is attached to the stacker frame and 20 the other to the stacker head. When the stacker so that the base members will pivot it is stopped quite suddenly with the result that the momentum of the parts exert sufficient force to raise the front end of the 25 stacker so that the base member will pivot about their rear ends and move from the full line to the dotted line position (Fig. 3) and back again. This periodic up and down movement keeps the braces from becoming too solidly clamped between the hay and the ground so that they may be more readily withdrawn. When the stack is finished and the stacker is to be removed, the pins 23 and 30 35 28 are first withdrawn after which the stacker may be moved to any place desired. The brace bar 20 is then removed by a straight pull which causes it to become separated from bar 19 in the manner shown in Fig. 4. The brace bar 19 may now be removed by a 40 45 straight pull.

I want to call particular attention to the fact that brace bars 19 and 20 together with the transverse bar 29, forms a triangle that is rigid and strong. The fact that the base member 2 extends slightly to the rear of the bar 29 should not be construed as a sufficient departure from a triangle to make that term inaccurate as the effect is practically the same. The base member 2 might be terminated exactly to the rear of the bar 19, but this would make it necessary to dispense with the plate 27. I also desire to call attention to the fact that the bars 19 and 20 are so connected to each other that they can be readily separated, in the manner shown in Fig. 4. This makes it possible to remove them from underneath the stack which could not be done if they were not connected in such a manner that this were possible. 50 55 60 65 The rigid structure that results from the ar-

rangement obviates bending strains and produces an effective anchoring means.

Having now described my invention, what I claim as new is:

1. A stacker frame, comprising, in combination, two parallel base members, connected near their rear ends by a transverse bar, a brace bar, connected to one of said base members and extending rearwardly in a straight line therefrom and another brace 70 bar connected to the other base member and extending diagonally into contact with the first mentioned bar, whereby the transverse bar and the two brace members form a substantially triangular structure. 80

2. In a stacker frame, comprising, in combination a pair of parallel spaced base members and a transverse bar connecting said members, an anchoring device adapted to project underneath a hay stack, said device comprising two straight bars, one of which has a diagonal opening near one end and the other of which is provided with a pin adapted to enter said opening, each of said bars having their spaced ends provided with means for connecting them to the ends of the base members and means for pivotally connecting said brace bars to said base members. 85

3. A stacker frame having two parallel spaced base members and an anchoring device attached to one end thereof, said anchoring device comprising two straight bars, one of which has one end connected to the other bar and extending at an angle therefrom, the spaced ends of the two bars being detachably connected to the base members. 95

4. A stacker frame having two parallel spaced base members and an anchoring device attached to one end thereof, said anchoring device comprising two straight bars, one of which has a hole extending diagonally therethrough and the other of which has a straight pin adapted to enter said hole and to hold the bars in angular relation and means for detachably connecting the spaced ends of said bars to the base members. 100 105 110

5. A hay stacker comprising, in combination, a base frame adapted to rest upon the ground, a stacker head pivotally connected to the frame, means for moving said stacker head about its pivot and an anchoring device attached to said frame, said anchoring device comprising two angularly related bars secured to one end of said frame so as to form with the latter a triangle. 115 120

6. A hay stacker frame having two bars removably connected to one end thereof, said bars being connected at a point spaced from the stacker frame so as to form with the latter a triangle. 125

7. A hay stacker frame having a triangular anchoring device at one end, said device being formed by two separable bars having adjacent ends attached to each other. 130

8. A stacker device comprising, in combination, a frame adapted to rest upon the ground, said frame having a transverse bar member, an anchoring device pivotally attached to said frame, said device comprising two angularly related bars one of which is provided with an opening and the other of which has a bolt projecting from its end, said bolt being adapted to enter said opening and means for pivotally connecting said bars to said frame.

9. A stacker frame adapted to rest upon the surface of the ground and an anchoring device attached thereto at a point spaced 15 from the end whereby the rocking of the frame will rock the anchoring device.

10. A stacker device having a frame adapted to rest upon the ground, a stacker arm pivotally attached to the frame, means for moving said arm about its pivot, means 20 for limiting said movement, said means being attached to the stacker arm and stacker frame and an anchoring device attached to the stacker frame near one end, said device projecting from the frame so as to be adapted to project underneath a haystack and means for raising the end of the anchoring device that is attached to the frame when the latter is tilted.

In testimony whereof I affix my signature.

JOSEPH H. COPE.
